Harry S. Gaither

Inventor:
James B. Horne
by Sheldon Jones, Sheldon & Smith
Atty's

UNITED STATES PATENT OFFICE.

JAMES B. HORNE, OF ST. CHARLES, ILLINOIS.

CIGARETTE TRAY.

Application filed May 10, 1919. Serial No. 298,104.

To all whom it may concern:

Be it known that I, JAMES B. HORNE, a citizen of the United States, residing at St. Charles, in the county of Kane and State of Illinois, have invented certain new and useful Improvements in Cigarette Trays, of which the following is a specification.

The purpose of this invention is to provide an improved tray or container adapted to hold cigars or cigarettes and to receive the butts and ashes thereof. The principal object of the invention is to provide a tray in which the ashes of the cigars or cigarettes are contained within a substantially closed chamber, so that the burning remnants are automatically extinguished and the ashes are prevented from blowing about. The invention comprises a bowl having a removable cover which is provided with an aperture to receive the ashes and the butts of the cigars or cigarettes, and an important feature of the invention lies in the provision of an auxiliary ash receiving trough in the cover in combination with ribs or flanges adapted to hold the cigars or cigarettes before they have been consumed.

Other objects of the invention will appear more clearly from the following specification, taken with the accompanying drawings, in which one embodiment is illustrated.

In the drawings—

Figure 1 shows a top plan view of a cigarette tray embodying the invention; and

Fig. 2 shows a vertical sectional view taken on the line 2—2 of Fig. 1.

The invention comprises a bowl 10 of brass or the like, the outer surface of which is preferably enameled or painted and furnished with an artistic design. The outer walls of the bowl 10 are cylindrical, and they converge downwardly toward the bottom 10^a which is concaved upwardly, as shown, so that the bowl has an annular contacting line or surface 10^b adapted to rest on a table or desk. A cover 11 is detachably mounted upon the upper end of the bowl 10, being provided with an annular flange 12 which extends downwardly around the outer wall of the bowl. The cover is curved upwardly from the flange 12, forming a rib 13, and within this rib the cover is provided with an annular depression or trough 14. The inner wall of the depression 14 is inclined upwardly and is connected to a downwardly converging funnel 15 in the form of an inverted

cone which terminates below the level of the annular depression 14. The converging walls of the funnel 15, and the inner wall of the trough 14, form an annular rib 16 which is located above the level of the annular rib 13.

Cigarettes or cigars may be supported by the ribs 13 and 16 or by the trough 14. When a cigarette is laid on the tray in the manner illustrated in the drawings, for example, the ashes will drop naturally into the center opening and fall into the chamber of the bowl. The upwardly projecting annular flange 16 makes it convenient to knock the ashes off of a cigar or cigarette into the funnel 15, and any stray ash which does not enter the funnel will be caught by the annular surrounding trough 14. When the cigar or cigarette has been consumed, the butt may be dropped through the funnel, and the lack of any air circulation within the bowl will automatically extinguish the contents of the bowl. This tray has the advantage that it provides a convenient support for a cigar or cigarette, while preventing the ash from blowing about, and at the same time the cover and bowl are designed to present an ornamental appearance.

Although I have shown and described a single embodiment of the invention for purposes of illustration, it will be understood that it may be constructed in various other forms without departing from the scope of the appended claims.

What I claim is:

1. The combination in a device of the class described of a bowl, and a removable cover therefor, said cover being provided with a downwardly extending funnel and a pair of annular ribs between said funnel and the circumference of said cover.

2. A device of the class described comprising a bowl and a cover detachably mounted on the upper end of said bowl, said cover being provided with an annular rib and a cone-shaped funnel portion surrounded by said rib and extending downwardly therefrom, said cover being further provided with an annular trough around said rib and a second annular rib adjacent the outer edge of said cover.

In testimony whereof, I have subscribed my name.

JAMES B. HORNE.
